UMBRELLA

Edward Okun, New York, N. Y., assignor to American Folding Umbrella Corporation, New York, N. Y., a corporation of New York

Application April 17, 1940, Serial No. 330,037

20 Claims. (Cl. 135—31)

This invention relates to umbrellas, and more particularly umbrella frames.

Umbrellas comprise an umbrella stick, ribs pivoted to the upper end of the stick by a rib retainer, and spreaders extending between the ribs and a runner which is slidable on the stick. The prevalent practice is to make the ribs and spreaders out of channel-shaped members. These are relatively rigid. They cannot be bent sideways without collapsing. They cannot be bent in the direction of the closed side of the channel. The ribs are made broader and shallower than the spreaders, and can be bent in the direction of the open side of the channel, but even these cannot be bent beyond a limited amount, for otherwise the metal will give and the rib will remain set in its bent position. The channels are formed of thin sheet metal and must be tempered exactly right, for otherwise they will collapse when put under bending stress. Professional umbrella buyers commonly test an umbrella by pulling the middle of the spreader in order to bend the same and so reveal weakness resulting from improper tempering. It is very difficult to obtain the exact desired uniform temper when working with a thin sheet metal channel.

If the umbrella is blown inside out by a strong wind, it is ruined, for the stiff nature of the channel ribs will not permit the umbrella to be drawn back to proper position.

The channel structure presents other difficulties. It is not practicable to electro-plate, and, therefore, is commonly enamelled or painted. The paint wears off, particularly at the sharp edges where the coating is always very thin. This permits rusting, which also invariably takes place at the pivots because of the wear at those pivots. Rust shortens the life of the umbrella.

The primary object of my invention is to generally improve umbrellas, and to overcome the foregoing difficulties and disadvantages. In accordance with my invention, each rib and spreader is preferably made of a pair of collaterally disposed spring wires. These wires may be of ordinary round section, thereby minimizing their cost. They may be made of steel, and are readily uniformly tempered. They are flexible in all directions, and if the umbrella is blown inside out by a particularly strong wind, it may be restored to useful condition by simply pulling the runner along the stick as though closing the umbrella. The ribs and spreaders are readily electro-plated and so may be coated with nickel, chromium, or, in the case of more expensive umbrellas, with gold. Connections at the ends of

the ribs and spreaders are made through special fittings preferably formed out of sheet brass, although other non-rusting material, such as nickel-silver, may be used. The finished frame has a beautiful appearance which is set off to good advantage by its contrast with the fabric covering of the umbrella. The frame is rust-proof and long lived. It is light in weight and closes compactly.

To the accomplishment of the foregoing and other objects, which will hereinafter appear, my invention consists in the umbrella frame elements and their relation one to the other, as hereinafter are more particularly described in the specification and sought to be defined in the claims. The specification is accompanied by drawings, in which:

Fig. 1 is a perspective view showing a single rib and spreader in open condition;

Fig. 2 is a similar view showing the relation sometimes taken by the parts when the umbrella is turned inside out;

Fig. 3 illustrates how the umbrella may be restored to normal condition by pulling the runner along the stick;

Fig. 4 is a side elevation of a rib and spreader with the parts drawn to enlarged scale;

Fig. 5 is a bottom plan view of a spreader attached to a runner, the tubular stick being shown in section;

Fig. 6 is a bottom plan view of a rib with the spreader removed;

Figs. 7, 8, 9 and 10 are top and side and end elevations, respectively, of an end pivot fitting in open condition;

Figs. 11 and 12 are front and end elevations, respectively, of a fitting intended to be applied to a rib to pivotally receive a spreader;

Figs. 13 and 14 are front and end elevations, respectively, of an end tip fitting;

Fig. 15 is a transverse section across any of the fittings;

Fig. 16 illustrates the roughening or knurling of a wire to receive a fitting;

Fig. 17 shows an umbrella embodying features of my invention, the umbrella being in open condition; and

Fig. 18 is a generally similar view showing the umbrella blown inside out without injury.

Referring to the drawings, and more particularly to Fig. 6, the umbrella rib comprises a collaterally disposed pair of wires 12 and 14. These are preferably round steel spring wires. They are provided with an end pivot fitting 16, a connector fitting 18, and an end tip fitting 20. The

spreader of the umbrella (see Fig. 5) is also made of a collaterally disposed pair of wires 22 and 24. These are provided at their ends with end pivot fittings 26 and 28. The end pivot fittings may be identical with one another and with the end pivot fitting 16 on the rib.

Referring now to Fig. 1, the end pivot fitting 16 of the rib is pivotally received in one of the radial slots of a rib retainer 30. This may be of conventional type, and is fixed at the upper end of an umbrella stick 32 in any known manner. The umbrella stick is preferably a duraluminum tube, this having the advantage of being light in weight, and being beautifully, lustrosly colored, if desired, by known electro-chemical processing.

The end tip fitting 26 of the spreader is similarly pivotally received in one of the radial slots of a suitable runner 34, which is slideable on stick 32. The end pivot fitting 28 of the spreader is received in the connector fitting 18 of the rib. It will be understood that the rib wires and the spreader wires lie in planes transverse to the umbrella stick, when the umbrella is open, that is, they are side by side in horizontal direction when the stick is vertical. The end tip fitting 20 of the rib preferably receives a conventional ornamental tip 36.

In Fig. 1 the parts are shown in the position which they assume when the umbrella is open, the runner 34 being disposed above the main catch 38. The relation of the parts is such that the umbrella is not readily turned or blown inside out. However, if subjected to an unusually high wind or gale it may be turned inside out, the parts then assuming the relation shown in Fig. 2. Because of the nature of the round spring wires used for the ribs, they are not injured by being bent in the reverse direction shown in Fig. 2. In most of the ribs the wires remain side by side in simple collateral relation. Often, however, one wire crosses the other, as is shown in the drawing. To restore the umbrella to useful condition, it is merely necessary to draw the runner 34 downwardly on stick 32, the catch 38 being pushed inwardly, of course, to permit the necessary downward movement, just as when closing any ordinary umbrella. As the runner 34 moves downwardly, the ribs are pulled into a more sharply defined curvature, as is shown in solid lines in Fig. 3. There is a critical point, however, at which further movement of the runner causes the ribs to spring from the reversely curved position, shown in solid lines, to the straight position, shown in broken lines. At this time any crossed wires resume their original collateral relation. The umbrella may then be either closed or opened in the normal way.

This feature of the umbrella is also illustrated by comparison of Figs. 17 and 18 of the drawings. In Fig. 17 the umbrella is shown in its normal open condition. Fig. 18 is a similar view looking in the same general direction, but with the umbrella shown turned or blown inside out. The reverse curvature is readily accommodated by the collaterally disposed round spring wires, and no injury results.

For a more detailed description of the construction of the umbrella, reference is next made to Figs. 7 through 10 of the drawing which show an end pivot fitting prior to its attachment to the spring wires. The fitting is formed out of sheet brass or other suitable and preferably rust-proof metal. The brass is preferably one-quarter hard when in sheet form, and is brought up to

one-half hard by the working of the metal in its shaping die. While the dimension is not critical, I have obtained excellent results using brass having a thickness of .025 inch.

The entire fitting is formed of a single piece of metal and comprises side walls 40 joined by a connecting wall 42. It is these walls that are curled or folded around and compressed against the ends of the spring wires, as will be clear from inspection of the fitting 26 in Fig. 5, and the showing of Fig. 15.

Projecting beyond the ends of the wires, the fitting comprises bearing walls 44 connected by an integral web 46. The side walls 44 are perforated at 48 to receive a suitable pivot, such as the wire commonly used on a rib retainer or on a runner. The walls 44 are shown with a small space therebetween, but this may be closed up if desired when the fitting is clamped on the wires. The only advantage of closing the walls 44 is to adapt the same to be received in the slots of a conventional rib retainer and runner.

It will be observed that the parts 44, 46 are preferably offset downwardly from the parts 40, 42. This makes it possible for the perforations 48 to be offset from the plane of the wires. Thus, referring to Fig. 4, the fitting 16 is so faced as to bring the pivot nearer the rib retainer 30. The fitting 26 is so faced as to bring its pivot nearer the runner 34. The fitting 28 is so faced as to bring its pivot near the connector 18. On reflection, it will be understood that this relation of the parts makes it possible for the umbrella to close compactly with the spreaders nested parallel to the ribs and both nested parallel to the stick. The end pivot fittings 26 and 28 on the spreader are alike, but are faced in opposite directions. This will also be seen in Fig. 5 in which the open side of fitting 26 is visible in contrast with the closed side of fitting 28.

Referring now to Figs. 11 and 12, the connector fitting consists of a piece of sheet brass bent to form side walls 50 connected by a bottom wall 52, the side walls having perforated ears 54 projecting upwardly therefrom. A somewhat lighter weight of metal may be used for this fitting, and I have had good results using brass .020 in thickness. It will be understood that the fitting is shown in open condition in Figs. 11 and 12. When it is applied to the rib wires, the side walls 50 are curled or folded about the wires and compressed tightly thereagainst. This brings the ears 54 to closer spacing, as is best shown in Fig. 6. It will be understood that a section across either end of fitting 18 would be substantially the same as that shown in Fig. 15.

The end tip fitting is shown in Figs. 13 and 14. This is also preferably formed of .020 thickness of sheet brass. It comprises side walls 56 joined by an integral bottom wall 58. Narrower side walls 60 project beyond the walls 56. In fact, the blank, if in flat condition, would be somewhat T-shaped, but with the parts exaggeratedly broad. When the fitting is applied to the wires, the walls 56 are folded or curled about the ends of the wires and compressed thereagainst. At the same time the narrower walls 60 are curled around to form a single tubular extension projecting midway between the wires as is shown at 62 in Figs. 4 and 6. This tubular projection is adapted to receive the ornamental fitting 36 (Fig. 4).

The dimension of the steel spring wires is not critical, but I have obtained good results using

a wire which is .058 inch in diameter for the ribs, and .062 inch in diameter for the spreaders.

While, perhaps, not essential, the ends of the wires are preferably roughened or knurled to receive the fittings. This is indicated in Fig. 16. A simple die may be used having two V-shaped portions which are struck toward one another on opposite sides of the wire in a suitable press, thereby making four lines of ridges or indentations. The fittings, while moderately hard, are much softer than the steel spring wire, and consequently when the fittings are clamped or compressed tightly against the wires the parts are interlocked with a secure engagement. The rib wires 12 and 14 may also be knurled at an intermediate point where the connector fitting 18 is attached.

After the fittings have been applied to the wires, the parts may be electro-plated with any desired finish, such as nickel, chromium, or gold plating.

It is believed that the construction and operation, as well as the many advantages of my improved umbrella, will be apparent from the foregoing detailed description thereof. The umbrella opens with a luxuriant, smooth, velvety feeling. This is due not only to the flexibility of the ribs, but probably to some extent because of a longitudinal compressibility of the spreaders, for the wires may spread apart somewhat under longitudinal compression, as is indicated by the wires 22 and 24 in Fig. 5. When the umbrella is open the spreaders may be pulled or shaken without damage for they bend freely and the ribs tend to bend somewhat along with the spreaders. In windy weather the umbrella may be held against the wind, and the entire rib and spreader structure yields somewhat, as may be necessary at one point or another, to buffet the wind, without damage to the parts. If a strong wind is inadvertently caught inside the umbrella, so that the umbrella happens to be turned inside out, it can be pulled back to initial condition without damage. The pivotal or working parts of the umbrella are made of non-ferrous or rust-proof metal, and the entire frame may be plated with a rust-proof coating. When plated with nickel, chromium, or gold, the frame has a beautiful contrasting appearance with the fabric of the umbrella. The parts being made of round wires, they are flexible in all directions and have no sharp edges where they may be imperfectly coated and where rust might begin.

It will be apparent that while I have shown and described my invention in a preferred form, many changes and modifications may be made in the structure disclosed without departing from the spirit of the invention as sought to be defined in the following claims.

I claim:

1. An umbrella comprising an umbrella stick, rib retainer, ribs, and spreaders, each of the ribs of said umbrella comprising a pair of collaterally disposed wires extending uninterruptedly from the rib retainer to the tip of the rib, said wires being individual separate normally-straight wires lying in a plane transverse to the umbrella stick when the umbrella is open, said wires over most of their length being relatively movable for maximum flexibility of the structure.

2. An umbrella comprising an umbrella stick, rib retainer, ribs, and spreaders, each of the ribs of said umbrella comprising a pair of collaterally disposed round steel spring wires extending un-

interruptedly from the rib retainer to the tip of the rib, said wires being individual separate normally-straight wires lying in a plane transverse to the umbrella stick when the umbrella is open, said wires over most of their length being relatively movable for maximum flexibility of the structure.

3. An umbrella comprising an umbrella stick, ribs, runner, and spreaders, each of said spreaders comprising a pair of collaterally disposed wires extending from the runner to a rib, said wires being individual separate normally-straight wires lying in a plane transverse to the umbrella stick when the umbrella is open, said wires over most of their length being relatively movable for maximum flexibility of the structure.

4. An umbrella comprising an umbrella stick, ribs, runner, and spreaders, each of said spreaders comprising a pair of collaterally disposed round steel spring wires extending from the runner to a rib, said wires being individual separate normally-straight wires lying in a plane transverse to the umbrella stick when the umbrella is open, said wires over most of their length being relatively movable for maximum flexibility of the structure.

5. An umbrella comprising an umbrella stick, rib retainer, ribs, runner, and spreaders, each of said ribs comprising a pair of collaterally arranged wires extending uninterruptedly from the rib retainer to the tip of the rib and each of said spreaders comprising a pair of collaterally arranged wires extending from the runner to a rib, said wires being individual separate normally-straight wires lying in a plane transverse to the umbrella stick when the umbrella is open, said wires over most of their length being relatively movable for maximum flexibility of the structure.

6. An umbrella comprising an umbrella stick, rib retainer, ribs, runner, and spreaders, each of said ribs comprising a pair of collaterally arranged round steel spring wires extending from the runner to a fitting on both wires of a rib, said wires being individual separate normally-straight wires lying in a plane transverse to the umbrella stick when the umbrella is open, said wires over most of their length being relatively movable for maximum flexibility of the structure.

7. An end pivot fitting for an umbrella part comprising a pair of collateral wires, said end pivot fitting being made of sheet brass or like rust-proof metal and having a part curled around and compressed against the end of one of the wires and another part curled about and compressed against the end of the collateral wire, the remainder of said fitting projecting beyond the ends of the wires and being shaped to form adjacent parallel side walls which are substantially offset from the plane of the wires and perforated at a point substantially offset from the plane of the wires to receive a pivot.

8. An umbrella comprising an umbrella stick, a rib retainer, ribs and spreaders, each of said ribs comprising a pair of collaterally arranged wires extending uninterruptedly from the rib retainer to the rib tip, and an end tip fitting consisting of a sheet metal body having a part curled around and compressed against the outer end of one of the wires, and having another part curled around and compressed against the outer end of the other wire while the remainder of the

- fitting projects beyond the ends of the wire for receiving a conventional ornamental tip, said wires being individual separate normally-straight wires lying in a plane transverse to the umbrella stick when the umbrella is open, said wires over most of their length being relatively movable for maximum flexibility of the structure.
9. An umbrella comprising an umbrella stick, a rib retainer, ribs, and spreaders, each of said ribs comprising a pair of collaterally arranged wires extending uninterruptedly from the rib retainer to the rib tip, an end pivot fitting for connecting the inner ends of said wires together and to the rib retainer, said fitting comprising a piece of sheet metal having a part curled around and compressed against the end of one of the wires and another part curled about and compressed against the end of the collateral wire, the remainder of said fitting projecting beyond the ends of the wires and being shaped to form adjacent parallel side walls, said side walls being offset from the plane of the wires and being perforated to receive the pivot of the rib retainer, said wires being individual separate normally-straight wires lying in a plane transverse to the umbrella stick when the umbrella is open, said wires over most of their length being relatively movable for maximum flexibility of the structure.
10. An umbrella comprising an umbrella stick, a rib retainer, ribs, and spreaders, each of said ribs comprising a pair of collaterally arranged wires extending uninterruptedly from the rib retainer to the rib tip, an end pivot fitting for connecting the inner ends of said wires together and to a rib retainer, said fitting comprising a piece of sheet metal having a part curled around and compressed against the end of one of the wires and another part curled about and compressed against the end of the collateral wire, the remainder of said fitting projecting beyond the ends of the wires and being shaped to form adjacent parallel side walls perforated to receive the pivot of the rib retainer, and an end tip fitting consisting of a sheet metal body having a part curled around and compressed against the outer end of one of the wires, and having a part curled around and compressed against the outer end of the other wire while the remainder of the fitting projects beyond the ends of the wire for receiving a conventional ornamental tip, said wires being individual separate normally-straight wires lying in a plane transverse to the umbrella stick when the umbrella is open, said wires over most of their length being relatively movable for maximum flexibility of the structure.
11. An umbrella comprising an umbrella stick, a rib retainer, ribs, and spreaders, each of said ribs comprising a pair of collaterally arranged round steel spring wires extending uninterruptedly from the rib retainer to the rib tip, and having knurled ends, an end pivot fitting for connecting the inner ends of said wires together and to the rib retainer, said fitting comprising a piece of sheet brass or like rust-proof sheet metal having a part curled around and compressed against the knurled end of one of the wires and another part curled about and compressed against the knurled end of the collateral wire, the remainder of said fitting projecting beyond the ends of the wires and being shaped to form adjacent parallel side walls which are connected by an integral web of metal, said walls being offset from the plane of the wires and perforated to receive the pivot of the rib retainer, and an end tip fitting consisting of a somewhat T-shaped sheet metal body made of brass or like rust-proof metal, the upper part of the T-shaped body having one end knurled around and compressed against the outer end of one of the wires, and having its other end curled around and compressed against the outer end of the other wire while the remainder of the fitting projects beyond the ends of the wire and is curled to itself form a single tubular end for receiving a conventional ornamental tip, said wires being individual separate normally-straight wires lying in a plane transverse to the umbrella stick when the umbrella is open, said wires over most of their length being relatively movable for maximum flexibility of the structure.
12. An umbrella comprising an umbrella stick, ribs, and spreaders, each of said spreaders comprising a pair of collaterally disposed wires, and an end pivot fitting at each end of the spreader, each of said fittings being made of sheet metal and having a part curled around and compressed against the end of one of the wires and another part curled about and compressed against the end of the collateral wire, the remainder of said fitting projecting beyond the ends of the wires and being shaped to form adjacent parallel side walls which are perforated to receive a pivot, said wires being individual separate normally-straight wires lying in a plane transverse to the umbrella stick when the umbrella is open, said wires over most of their length being relatively movable for maximum flexibility of the structure.
13. An umbrella comprising an umbrella stick, ribs, and spreaders, each of said spreaders comprising a pair of collaterally disposed round steel spring wires having knurled ends, and an end pivot fitting at each end of the spreader, each of said fittings being made of sheet brass or like rust-proof sheet metal and having a part curled around and compressed against the knurled end of one of the wires and another part curled about and compressed against the knurled end of the collateral wire, the remainder of said fitting projecting beyond the ends of the wires and being shaped to form adjacent parallel side walls which are connected by an integral web of metal, said walls being perforated to receive a pivot, said wires being individual separate normally-straight wires lying in a plane transverse to the umbrella stick when the umbrella is open, said wires over most of their length being relatively movable for maximum flexibility of the structure.
14. An umbrella comprising an umbrella stick, ribs, and spreaders, each of said spreaders comprising a pair of collaterally disposed wires, and an end pivot fitting at each end of the spreader, each of said fittings being made of sheet metal and having a part curled around and compressed against the end of one of the wires and another part curled about and compressed against the end of the collateral wire, the remainder of said fitting projecting beyond the ends of the wires and being shaped to form adjacent parallel side walls, said walls being offset from the plane of the wires and perforated to receive a pivot, the fitting at one end of the spreader facing in opposite direction to the fitting at the other end of the spreader, whereby the offset perforations help produce compact closing of the umbrella.
15. An umbrella comprising an umbrella stick, ribs, and spreaders, each of said spreaders comprising a pair of collaterally disposed round steel spring wires having knurled ends, and an end pivot fitting at each end of the spreader, each of said fittings being made of sheet brass or like

- rust-proof sheet metal and having a part curled around and compressed against the knurled end of one of the wires and another part curled about and compressed against the knurled end of the collateral wire, the remainder of said fitting projecting beyond the ends of the wires and being shaped to form adjacent parallel side walls which are connected by an integral web of metal, said walls being offset from the plane of the wires and perforated to receive a pivot, the fitting at one end of the spreader facing in opposite direction to the fitting at the other end of the spreader, whereby the offset perforations help produce compact closing of the umbrella.
15. An umbrella comprising an umbrella stick, ribs, and spreaders, each of said ribs and spreaders comprising a pair of collaterally arranged wires, end pivot fittings at the inner end of the rib and at both ends of the spreader, each of said end pivot fittings being made of sheet metal having a part curled around and compressed against the end of one of the wires and another part curled about and compressed against the end of the collateral wire, the remainder of said fitting projecting beyond the ends of the wires and being shaped to form adjacent parallel side walls which are perforated to receive a pivot, and a connector fitting clamped at an intermediate point on the rib wires and having perforated ears pivotally receiving one end pivot fitting of the spreader, 30 said wires being individual separate normally-straight wires lying in a plane transverse to the umbrella stick when the umbrella is open, said wires over most of their length being relatively movable for maximum flexibility of the structure.
17. An umbrella comprising an umbrella stick, ribs and spreaders, each of said ribs and spreaders comprising a pair of collaterally arranged round steel spring wires having knurled ends, end pivot fittings at the inner end of the rib and at both ends of the spreader, each of said end pivot fittings being made of sheet brass or like rust-proof sheet metal having a part curled around and compressed against the knurled end of one of the wires and another part curled about and compressed against the knurled end of the collateral wire, the remainder of said fitting projecting beyond the ends of the wires and being shaped to form adjacent parallel side walls which are connected by an integral web of metal, said walls being offset from the plane of the wires and perforated to receive a pivot, the end fitting of the rib being offset toward the umbrella stick, 35 and the end fittings of the spreader being faced in opposite direction so that the offset perforations help obtain compact closing of the umbrella, a connector fitting made of sheet brass or like rust-proof metal and clamped at an intermediate point on the rib wires and having perforated ears pivotally receiving one end pivot fitting of the spreader, and an end tip fitting at the outer end of the rib, said fitting consisting of a somewhat T-shaped sheet metal body made of brass 40 or like rust-proof metal, the upper part of the T-shaped body having one end curled around and compressed against the knurled end of one of the wires and having its other end curled around and compressed against the knurled end of the other wire while the lower part of the fitting projects beyond the ends of the wire and is curled to itself form a single tubular end for receiving a conventional ornamental tip.
18. An umbrella comprising an umbrella stick, ribs, and spreaders, each of said ribs and spreaders comprising a pair of collaterally arranged wires, end pivot fittings at the inner end of the rib and at both ends of the spreader, each of said end pivot fittings being made of sheet metal having a part curled around and compressed against the end of one of the wires and another part curled about and compressed against the end of the collateral wire, the remainder of said fitting projecting beyond the ends of the wires

and being shaped to form adjacent parallel side walls which are connected by an integral web of metal, said side walls being offset from the plane of the wires and perforated to receive a pivot, the end fitting of the rib being offset toward the umbrella stick, and the end fittings of the spreader being faced in opposite direction so that the offset perforations help obtain compact closing of the umbrella, and a connector fitting clamped at an intermediate point on the rib wires and having perforated ears pivotally receiving one end pivot fitting of the spreader.

19. An umbrella comprising an umbrella stick, ribs, and spreaders, each of said ribs and spreaders comprising a pair of collaterally arranged round steel spring wires having knurled ends, end pivot fittings at the inner end of the rib and at both ends of the spreader, each of said end pivot fittings being made of sheet brass or like rust-proof sheet metal having a part curled around and compressed against the knurled end of one of the wires and another part curled about and compressed against the knurled end of the collateral wire, the remainder of said fitting projecting beyond the ends of the wires and being shaped to form adjacent parallel side walls which are connected by an integral web of metal, said side walls being offset from the plane of the wires and perforated to receive a pivot, the end fitting of the rib being offset toward the umbrella stick, 30 and the end fittings of the spreader being faced in opposite direction so that the offset perforations help obtain compact closing of the umbrella, a connector fitting made of sheet brass or like rust-proof metal and clamped at an intermediate point on the rib wires and having perforated ears pivotally receiving one end pivot fitting of the spreader, and an end tip fitting at the outer end of the rib, said fitting consisting of a somewhat T-shaped sheet metal body made of brass 40 or like rust-proof metal, the upper part of the T-shaped body having one end curled around and compressed against the knurled end of one of the wires and having its other end curled around and compressed against the knurled end of the other wire while the lower part of the fitting projects beyond the ends of the wire and is curled to itself form a single tubular end for receiving a conventional ornamental tip.

20. An umbrella comprising an umbrella stick, 50 a rib retainer, ribs, a runner, and spreaders, each of the ribs of the umbrella comprising a collaterally disposed pair of spring wires extending continuously from the rib retainer to the tip of the rib, said wires being individual separate normally-straight wires lying in a plane transverse to the umbrella stick when the umbrella is open, said wires over most of their length being relatively movable for maximum flexibility of the structure, the resulting rib being flexible in the 60 direction of the umbrella stick, the ribs of the umbrella being so proportioned that if the umbrella is blown inside out it may be restored to normal condition without injury by simply moving the runner downwardly on the stick.

EDWARD OKUN.
